UNITED STATES PATENT OFFICE.

WILLIAM GEORGE DOLEY, OF TORRENSVILLE, SOUTH AUSTRALIA, AUSTRALIA.

LENS-GRINDING MACHINERY.

Application filed April 5, 1922. Serial No. 549,671.

To all whom it may concern:

Be it known that I, WILLIAM GEORGE DOLEY, a subject of His Majesty the King of Great Britain, and resident of 57 West 5 Street, Torrensville, in the State of South Australia, Commonwealth of Australia, have invented certain new and useful Improvements in and Connected with Lens-Grinding Machinery, of which the 10 following is a specification.

My invention relates to lens grinding machinery and comprises an improved arrangement of mechanism to impart to a lens holder two reciprocating movements 15 at right angles to one another causing the lens to be moved over the surface of the lapping tool, a stationary lapping tool being used for cylindrical and toric sections and a revolving lapping tool for spherical, hyperbolic or parabolic sections and the like.

According to this invention several units 20 or heads may be driven from the one driving point, each unit being self contained and adapted to be controlled independently 25 without in any way interfering with the operation of the other units.

Each unit of my lens grinding machinery 30 is housed in a box containing oil and provided with an oil pump and distributing pipes. Two shafts pass through the box from side to side, these shafts are driven at different speeds according to the desired 35 ratio of the reciprocating movements to be imparted to the lens holder. One of the shafts carries an eccentric block which is adapted to impart a quick rocking motion to a carriage pivoted upon a guide bar near the bottom of the casing while the other shaft also carries an eccentric block that 40 imparts a reciprocal sideways and slower movement to the same carriage. The carriage supports a hinged carrier for the lens holder which is thus moved by the carriage and is held upon the lapping tool 45 by adjustable spring devices.

The eccentric blocks are each provided 50 with a clutch, the two clutches being connected by a yoke and controlled from a lever on the outside of the casing.

But in order that my invention may be 55 more clearly understood I will now describe the same by the aid of the accompanying illustrative drawings wherein:

Fig. 1 is a plan of a unit of my lens 60 grinding machinery.

Fig. 2 is a section on line $x-y$ of Fig. 1.

Fig. 3 is a front elevation with part of case removed and with some of the parts at the rear omitted for clearness.

Fig. 4 is a front view of casing.

Fig. 5 is a side sectional elevation of carriage.

Fig. 6 is a plan of the bell crank.

Fig. 7 is a side elevation thereof.

Fig. 8 is a perspective view of bearing shoe for the bell crank.

Fig. 9 is a section of one of the bearings of the guide shaft.

In each of the illustrations similar letters of reference are used to denote similar or 70 corresponding parts wherever they occur.

The oil containing box a is provided with a lid or cover a' and has shafts passing through it from side to side and supported in bearings a^2 in the sides of the box.

One shaft b carries an eccentric block c that is adapted to impart a quick backward and forward rocking motion to the carriage d through its strap c' . The other shaft e carries an eccentric block f the strap f' 80 which is adapted to rock a bell crank g .

This bell crank g is mounted on a vertical spindle h and its other arm rests in a shoe j arranged between the cheeks of the carriage d so that it imparts a reciprocal sideways 85 movement thereto.

The carriage d is mounted on a guide shaft k by means of a sleeve d' so that it may rock and slide thereon simultaneously 90 while it also slidably rests upon the eccentric block c . The guide shaft k is supported in slip-in bearings l on the sides of the box, each of said bearings having an opening l' to receive the end of the shaft k which is cut away at k' to allow it to freely pass through the opening l' . At the upper part of the carriage d is a bar m that is hinged to the carriage at m' and extends forwardly through an opening n in the front of the box a .

At the front end this bar has two lugs or ears n' to which are connected the tension springs o the tension of which is controlled by a lever handle o' and is adjustable by means of nuts o^2 . The body of the bar m 105 has a hole through it in which is a shaft p that is held in position by a collar p' and is free to oscillate in a rotary manner in the bar m .

The forward end of the shaft p supports 110 the lens carrier q to which pressure is applied by the hinged bar m . The lapping

tool carrier r is adjustably supported in guides r' and is held in position by a clamp nut r^2 . When desired the lapping tool may be rotated as will be well understood.

- 5 The eccentric blocks are provided with friction clutches s which are connected by a yoke s' that is adapted to be moved by a fork s^2 on a rod s^3 controlled by a lever s^4 on the front of the box.
- 10 The shafts b and e may be driven independently as illustrated by belts t or they may be connected by suitable gear and driven by a single belt wheel. An oil pump u is operated by the eccentric f to supply 15 oil through pipes (not shown) to the parts of the mechanism.

By this means any number of units or heads may be coupled up and a battery of say six or eight heads may be used each 20 head being controlled independently of the others.

In operation the shafts b and e being rotated and the clutches s being in operative position the eccentric blocks c and f will 25 also be rotated. The eccentric block c will cause the carriage d to be rocked quickly backwardly and forwardly on the shaft b and simultaneously the eccentric block f will cause the bell crank g to reciprocate the 30 carriage sideways.

These movements cause the carriage to impart to the lens carrier reciprocal motions at right angles to one another, the lens being guided over the surface of the lapping tool and the required pressure being applied thereto by the springs o .

I claim:—

In lens grinding machinery, the combination of a casing, a fixed guide shaft therein, a carriage rotatably and slidably mounted on the guide shaft, a bar hinged to said carriage, a lens holder carried by said bar, means for applying pressure to said lens holder, and means for imparting to said carriage two reciprocal movements 45 perpendicular to each other, said last named means comprising two independently driven parallel driving shafts mounted in said casing, an eccentric block on each shaft, a strap carried by the carriage and in operative engagement with one of said blocks for rocking the carriage on said guide shaft, a strap in operative engagement with the other block, and a bell-crank articulated between said last named strap and the carriage 50 for sliding said carriage on said guide shaft.

In testimony whereof he has affixed his signature.

WILLIAM GEORGE DOLEY.
